STOKER

Speer W. Guthrie, Indiana, Pa., assignor to Pennsylvania Bituminous Coal Research, Inc., Altoona, Pa., a corporation of Pennsylvania

Application November 5, 1943, Serial No. 509,071

3 Claims. (Cl. 110—45)

This invention relates to stokers, more particularly to underfeed stokers which operate on the principle of partial oxidation of coal prior to its undergoing active combustion.

Underfeed stokers as ordinarily constructed do not operate satisfactorily with strongly coking coals, such as the Pennsylvania coking coals. That is, when it is attempted to burn a strongly coking coal in an underfeed stoker of customary construction there is a strong tendency for unburned coke to be formed and to accumulate and build up above the retort in a generally columnar form known as a coke tree. Coke trees burn primarily at the base, and the presence of a coke tree results in unsatisfactory combustion, especially when the demand on the heating unit is not great, they slow down the response of the furnace to demand for heat and cause overshooting of thermostatic control, and they make it difficult to maintain low hold-fire rates without danger of the fire going out. In fact, coke tree formation may become so extensive as actually to extinguish the fire or to push open the furnace door.

A method of and apparatus for avoiding the formation of coke trees from coking coals by mildly oxidizing the coal before active combustion begins is described and claimed in an application filed by Theodore S. Spicer and Calvert C. Wright on April 15, 1941, Serial No. 388,626. As the coal moves upwardly into and through the lower end of the retort of the stoker it is heated by conduction of heat downwardly from the actively burning coal, and in that portion of the column of coal in which the coal is heated but is not yet plastic, i. e., where coking has not begun, the coal is oxidized to an extent such as to reduce but not destroy its coking power. This oxidation is chiefly a surface phenomenon but it does not involve active combustion. This is accomplished by introducing an oxidizing agent, most suitably air or an air-steam mixture, into the coal at a point or in a region such that it comes into intimate contact with the heated but non-plastic coal. For brevity this procedure is referred to as a preoxidation method of operating a stoker, or as the preoxidation principle.

Extended experience has demonstrated amply that the preoxidation method easily and satisfactorily represses coke tree formation provided certain critical details are observed. In the first place, the coal must be mixed intimately with the oxidizing agent as it moves upwardly through the preoxidation zone. Second, as the coal is mixed and elevated any substantial segre-

gation must be avoided, i. e., it is necessary to maintain substantial uniformity of coal size distribution across the section while mixing it intimately with the oxidizing agent. These features, 5 result in subjecting all of the coal uniformly to the action of the preoxidizing air or other oxidizing agent, and observance of them is necessary because it has been found that coke tree suppression is not attained satisfactorily if the coal is not thoroughly mixed with the air or if the air distribution is not uniform due to channeling or segregation of the coal into regions containing largely fines and regions containing largely coarse particles. And as indicated above, the coal must 10 be heated but not sufficiently to render it plastic, and enough oxidizing agent must be supplied to produce the desired oxidation before coking of the coal begins.

Although the necessary elevation and mixing of 15 the coal without segregation in the preoxidation zone may be accomplished satisfactorily in various ways, the simplest and most effective means for doing so is a vertical screw. Likewise, although the oxidizing agent might be introduced 20 into the coal at any point prior to the preoxidation zone, it is preferred to supply the oxidizing agent through a supplementary, or preoxidizing, tuyère situated below the regular, or active combustion, tuyères at a distance such that the agent 25 enters the coal substantially at the lower end of the preoxidation zone.

It has been found in actual practice that in 30 the operation of such a stoker there may be a tendency for coal to enter the supplementary tuyère, even to the extent of closing the tuyère opening. This is serious because it decreases the amount of air supplied by the supplementary tuyère to the coal and coke trees result because the coal is not oxidized sufficiently. Moreover, 35 continued operation may completely fill the tuyère openings and by forcing coal through the tuyère cause the wind box to be filled with ridlings, which is obviously objectionable. Up to the time of this invention, however, no satisfactory solution of that difficulty had been found.

The major object of this invention is to provide 40 a stoker constructed and operated in accordance with the preoxidation principle with simple, inexpensive and automatic means for keeping the supplementary, or preoxidation, tuyère free from coal.

Other objects will appear from the following 45 description.

The invention will be described with reference 50 to the accompanying drawing in which Fig. 1

is a vertical sectional view through the significant part of a preoxidation type stoker constructed in accordance with one embodiment of the present invention; and Fig. 2 a horizontal section taken on line II--II, Fig. 1.

The invention is predicated on my discovery that accumulation of coal riddlings in the supplementary tuyère of a preoxidation type stoker can be avoided easily by providing the tuyère with a continuously unobstructed opening, and by providing a horizontally movable scraper member which is rotated in the tuyère opening to sweep it free from coal that may have found its way into the opening. This may be accomplished, for example, by connecting a scraper member to the vertical screw so that when the screw rotates during the on periods of the stoker the scraper continuously and automatically acts to keep the supplementary tuyère open.

Having reference now to the drawing, there is shown a preoxidation type of stoker comprising a retort 1 of conventional form provided with one or more main combustion tuyères which form the active combustion zone in the manner customary in the art. In the embodiment shown there are two such tuyères, shown at 2 and 3, Fig. 1. The retort is surrounded by a wind box 4 supplied with air or other oxidizing agent from a main air duct 5 in any suitable way, as by a motor driven blower. Coal is introduced to the retort by a horizontal screw 6 operating in a conduit 7. The blower which supplies air to main duct 5 and the screw conveyor 6 are operated in any suitable manner; such elements form no part of this invention, and because they are well understood in the art they do not require illustration or further description.

Coal is delivered by screw conveyor 6 to the bottom of the retort where it is picked up and moved upwardly by a vertical screw conveyor 8 operated by a gear 9 and a pinion 10 which may suitably be driven by the motor which operates screw 6. During the on periods of the stoker screw conveyor 8 moves the coal progressively and continuously upwardly through the retort into the active combustion zone and in so doing the coal is mixed without segregation of particles or pieces of varying size.

Disposed in wind box 4 is a partition 11 which divides it into an upper air chamber 12 through which air is supplied to the active combustion tuyères 2 and 3, and a lower air chamber 13 through which air is supplied to the preoxidation tuyère 14. Chambers 12 and 13 act as conduits for supplying air to the main and supplementary tuyères. Mounted at the juncture of wind box 4 and the main air duct for pivotal movement about the end of partition 11 is a butterfly valve 15. By moving it appropriately, as indicated by the broken line positions, Fig. 1, the air supplied through duct 5 may be apportioned in any desired manner between the upper and lower air chambers 12 and 13. This butterfly valve 15 may be adjusted in various ways, e. g., manually, according to need. Thus, all of the air may be passed to the upper tuyères 2 and 3, or all of it may be passed to the preoxidation tuyère 14. In ordinary practice, however, valve 15 will be adjusted to supply an amount of air to the preoxidation tuyère 14 which effects preoxidation sufficient to prevent coke tree formation, and air necessary for combustion is passed directly to the active combustion zone through upper air chamber 12 and tuyères 2 and 3. A smoke back opening 16 may be pro-

vided as shown in Fig. 1 for the usual purpose of preventing back pressure at this point.

The upper, or active combustion, tuyères 2 and 3 are, as will be observed from Fig. 1 of the usual sectional construction which forms a series of spaced openings between webs 2a and 3a. In accordance with the present invention, however, the preoxidation tuyère 14 has a continuously unobstructed opening, as shown in Fig. 1, to permit a scraper member 17 to enter the tuyère opening and to pass completely around it to sweep from the opening any pieces of coal or other material that may be forced into the tuyère opening by the action of the vertical screw when it operates to lift the coal upwardly into the retort.

The scraper may be mounted and actuated in various ways. In accordance with the preferred embodiment of the invention, however, scraper 17 is actuated automatically during the on periods of the stoker, which is the only time when it is necessary to clear tuyère 14. This is accomplished, in accordance with the invention, by connecting the scraper to vertical screw 8. Although this may be done in various ways, in the embodiment shown scraper 17 is connected directly, as by welding, to the blade of the screw at a point such that the scraper will move continuously through the tuyère opening under the action of the screw, as shown particularly in Fig. 1. In the embodiment shown in the drawing the scraper is in the form of a hook, or claw, and it is connected to the screw so that its concave face moves forwardly when the screw rotates, as indicated by the arrow, Fig. 2.

The operation of a stoker constructed in accordance with the drawing will be understood from what has been said above. Briefly, during the on periods of the stoker coal from a hopper or bin, not shown, passes through conduit 7 to the bottom of the retort and is there picked up by screw conveyor 8 and moved upwardly toward the active combustion zone. Air for preoxidation enters tuyère 14 which is situated at a level such that the temperature of the coal is sufficient for initiation of the desired preoxidation but insufficient to make it plastic. Under the combined action of mixing of conveyor 8 without substantial segregation and of the air introduced through tuyère 14, the coal is sufficiently oxidized by the time it reaches the plastic zone, which lies at or immediately above the upper end of conveyor 8, that coke trees do not form when the coal burns in the active combustion zone, i. e., in the region of tuyères 2 and 3. Meanwhile, rotation of screw 8 continuously moves scraper 17 through the opening of tuyère 14 to keep it free from coal that may be pushed into it under the thrust of the screw. In this way the tuyère continues to function without interference to repress coke tree formation.

Various modifications are, of course, permissible. For example, the scraper member may assume other forms or may be connected in other ways than shown in the drawing.

According to the provisions of the patent statutes, I have explained the construction and mode of operation of my invention and have illustrated and described what I now consider to represent its best embodiment. However, I desire to have it understood that, within the scope of the appended claims, the invention may be practiced otherwise than as specifically illustrated and described.

I claim:

1. An underfeed stoker comprising the combination of a substantially vertical retort provided with a main combustion tuyère at the upper portion where active combustion occurs, means for supplying coal to the lower end of said retort, a vertical screw disposed in said retort for moving coal upwardly in the retort while mixing it thoroughly and maintaining substantial uniformity of size distribution, the upper end of said screw being disposed below the plane of said tuyère, a supplementary tuyère having a continuously unobstructed opening disposed in the retort wall below said main combustion tuyère for supplying an oxidizing agent to the coal engaged by said screw in a region where the coal is heated but not plastic, conduits for supplying said oxidizing agent communicating with the said tuyères, and a scraper member connected to said screw and extending into said supplementary tuyère opening to rotate with the screw and sweep coal from said opening.

2. An underfeed stoker comprising the combination of a substantially vertical retort provided with a main combustion tuyère at the upper portion where active combustion occurs, means for supplying coal to the lower end of said retort, a vertical screw disposed in said retort for moving coal upwardly in the retort while mixing it thoroughly and maintaining substantial uniformity of size distribution, the upper end of said screw being disposed below the plane of said

tuyère, a supplementary tuyère having a continuously unobstructed opening disposed in the retort wall below said main combustion tuyère for supplying an oxidizing agent to the coal engaged by said screw in a region where the coal is heated but not plastic, conduits for supplying said oxidizing agent to the said tuyères, and a scraper member connected to the blade of said screw and extending into said supplementary tuyère opening to rotate with the screw and sweep coal from said opening.

3. An underfeed stoker comprising the combination of a substantially vertical retort provided with a main combustion tuyère at the upper portion where active combustion occurs, means for supplying coal to the lower end of said retort, a vertical screw disposed in said retort for moving coal upwardly in the retort while mixing it thoroughly and maintaining substantial uniformity of size distribution, the upper end of said screw being disposed below the plane of said tuyère, a supplementary tuyère having a continuously unobstructed opening disposed in the retort wall below said main combustion tuyère for supplying air to the coal engaged by said screw in a region where the coal is heated but not plastic, a wind box communicating with said tuyères for supplying air to them, and a scraper member connected to the blade of said screw and extending into said supplementary tuyère for keeping it clear of coal.
